Atty's.

UNITED STATES PATENT OFFICE.

RALPH M. GASTON, OF CHICAGO, ILLINOIS.

INTERNAL-COMBUSTION ENGINE.

1,351,950.

Specification of Letters Patent. Patented Sept. 7, 1920.

Application filed July 17, 1919. Serial No. 311,498.

To all whom it may concern:

Be it known that I, RALPH M. GASTON, a citizen of the United States, residing at Chicago, in the county of Cook and State of Illinois, have invented certain new and useful Improvements in Internal-Combustion Engines, of which the following is a specification.

This invention relates to internal combustion engines, and has reference more particularly to improvements in what are known as air-cooled engines, which dispense with the usual water jacket, and employ radially projecting ribs or fins on the cylinder casting to maintain the temperature of the cylinder at a working point.

One of the principal impediments to the successful operation of air-cooled engines has been the rapid deterioration of the valves and valve stems, and more particularly the exhaust valves and their stems from the high temperatures to which they are subjected. Most of the designs of air-cooled engines heretofore used give poor flexibility of control on account of poorly fitting valves and valve stems, which is the natural result of excessively high temperatures in these parts. This condition has usually existed even when the pistons were well lubricated and operated in a normal manner.

One object of this invention is to provide an improvement in the nature of a cooling feature for the valve stems.

It is also desirable in the interest of increased efficiency and reliability of operation to maintain not only the valve stems but their operating parts in as cool a condition as possible; and a further object of this invention is to provide an arrangement whereby the valve actuating devices are housed in a casing which is entirely independent of the cylinder walls and permits free air circulation between the cylinder or cylinders and the housing.

In the accompanying drawing, which is a vertical cross section through a cylinder, the crank case, the valve rocker casing, the exhaust valve, and the intake and exhaust manifolds, I have illustrated one embodiment of my present invention which, in practice, has been found to satisfactorily fulfil the above-stated objects.

Referring to the drawing, 5 designates the crank case, and 6 a cylinder secured thereon by a screw 7 and a clamping plate 8, said

cylinder having the usual radially projecting ribs or fins 9 commonly employed on air-cooled cylinders. Within the cylinder is the usual piston 10 connected by connecting rod 11 to the crank shaft 12. Extending through the crank case is the cam shaft 13 carrying the usual valve actuating cams, one of which is shown at 14 engaged with the lower end of a rocker arm 15 mounted on a pivot shaft 16 above the crank case. The upper end of the rocker arm 15 carries an adjusting screw 17, the head of which is engaged with the outer end of the stem 18 of the exhaust valve 19. The valve stem 18 is slidably mounted in a sleeve 20 that is fitted horizontally in an opening in the cylinder head and extends within a hole 21 formed in the body wall of the valve rocker casing 22, this latter being mounted on the crank case 5 and spaced some distance from the cylinder 6 and secured by a screw 23 and the clamp 8. The valve 19 is normally held upon its seat by a spring 24 located within the valve rocker casing and confined between the wall 22 and an abutment disk 25 on the outer end of the valve stem 18. A cover 26 is detachably secured to the main body of the valve rocker casing by screws 27.

Above the cylinder head extend the intake manifold 28 and the exhaust manifold 29, these being secured in place by a yoke 30 and clamping screws 31, it being understood that in multiple cylinder practice the cylinders are located side by side as usual, and the intake and exhaust manifolds extend lengthwise of and above the group.

Surrounding the valve sleeve 20 is a sleeve or collar 32 that is formed with a series of laterally projecting ribs or fins 33 similar in structure and function to the cylinder ribs 9. These cooling devices, are preferably applied to both the intake and exhaust valves which, in the organization shown, lie side by side in parallel alternating relation; but their value exists chiefly as an adjunct of the exhaust valve since it is the overheating of the latter that gives the most trouble in air cooled engines. By providing such a cooling device for the valve stems, overheating of the latter is prevented and they are maintained in good operating condition.

It will be further noted that between the valve rocker casing and the cylinder there is an open space for the free circulation of air between these parts, which not only keeps

the valves and stems below a dangerous temperature but reduces expansion from heat. This feature permits engine operation with small clearance between the upper 5 end of the rocker arm and the valve stem. This results in the same quiet operation that is obtained with high grade water cooled engines.

It will further be observed that the valve-
10 stem guide, comprising, in the instance shown, the sleeve 20 and collar 32, completely bridges the space between the cylinder and rocker casing, lying in tight surface contact with both, so that it not only radiates heat but also conducts a considerable portion of the cylinder heat to the rocker casing. This is of maximum value and importance where the collar 32 is made of aluminum or other metal of high heat conductivity.
15
20

In the cylinder head is the usual tapped opening 34 to accommodate a spark plug and also a tapped opening 35 containing a plug 36 lying opposite the valve 19, to facilitate application and removal of the valve. These features, however, are old and well known.

While I have found that the specific organization and arrangement herein shown and described works well in practice and fulfills the stated objects of the invention, it will be manifest that the arrangement might be considerably varied without detracting from the efficiency of the valve stem cooling 35 means and the free air circulation between the cylinder and the valve rocker casing. Hence I do not limit the invention to the particular organization and arrangement shown, except to the extent indicated in specific claims.
40

I claim:

1. In an air cooled internal combustion engine, the combination of an engine cylinder, a valve rocker casing located laterally opposite to and spaced from said cylinder, a valve stem guide extending between said cylinder and rocker casing and in contact with both whereby it serves to conduct heat from said cylinder to said rocker casing, heat radiating fins on the circumference of said guide, and a valve stem mounted in said guide.
45
50

2. In an air cooled internal combustion engine, the combination of an engine cylinder, a valve rocker casing located laterally opposite to and spaced from said cylinder, a guide-sleeve bridging the space between said cylinder and rocker casing, a valve stem mounted in said guide sleeve,
55

and a collar surrounding said guide sleeve 60 and formed on its circumference with heat-radiating fins, said collar at its ends lying in contact with said cylinder and casing, whereby said guide sleeve and collar both serve to conduct heat from said cylinder to 65 said casing.

3. In an air cooled internal combustion engine, the combination of an engine cylinder, a valve rocker casing spaced from said cylinder, a guide sleeve bridging the space 70 between said cylinder and rocker casing, a valve stem mounted in said guide sleeve, and a collar surrounding said guide sleeve and formed on its circumference with heat radiating fins, said collar at its ends lying 75 in contact with said cylinder and casing, whereby said guide sleeve and collar both serve to conduct heat from said cylinder to said casing.

4. In an air cooled internal combustion 80 engine, the combination of a support, a cylinder mounted on said support, a valve rocker casing mounted on said support at one side of and spaced from said cylinder, thereby permitting circulation of air between 85 said cylinder and valve rocker casing, a valve sleeve disposed between said cylinder and valve rocker casing, and a valve stem slidably mounted in said sleeve and having its outer end disposed within said valve rocker casing, and a valve-closing spring surrounding the portion of said valve stem lying within said valve rocker casing.
90
95

5. In an air-cooled internal combustion 95 engine, the combination of a crank case, a cylinder mounted on said crank case, a valve rocker casing mounted on said crank case at one side of and spaced from said cylinder, a valve rocker in said casing, a valve in 100 said cylinder having its stem extending between said cylinder and valve rocker casing, and a member surrounding said valve stem and formed with heat radiating ribs or fins.
105

6. In an air-cooled internal combustion engine, the combination of a crank case, a cylinder mounted on said crank case, a valve rocker casing mounted on said crank case at one side of and spaced from said cylinder, a valve rocker in said casing, a valve sleeve extending between and supported by said cylinder and valve rocker casing, a valve stem slidably mounted in said sleeve, and a collar surrounding said sleeve and formed 110 with heat radiating ribs or fins.
